Des. 1174

Jeremiah Meyer, of New York, assignor to Ridder & Son, of Manchester, N.H.
Letters Patent No. 1174, dated Dec² 20, 1850.

The schedule referred to in these Letters Patent and making part of the same.

To all whom it may concern:

Be it known that I, Jeremiah Meyer, of the City, County and State of New York, have invented or produced, a new and original and ornamental design or pattern for Floor Cloths, Carpets and other fabrics, and I do hereby declare that the accompanying pattern or drawing, Fresco No. 2, represents said Design and is sufficient without further aid to enable any person skilled in the Art to which it appertains to repeat it for practical use.

The colors and the arrangement of them may in the use of this design, be the same as shown in said pattern, or varied to suit the views or fancy of the user, or manufacturer of the article ornamented by said design.

What I claim as my invention or production and desire to secure by Letters Patent, is the Ornamental Design represented in the accompanying pattern.

Witnesses.

Exd, Samuel P. Bell,
S. M. P. John H. Aldrich.

Jeremiah Meyer.
